TOY HOWITZER

Roy Fitzgerald Constan, Staten Island, N.Y., assignor to Deluxe Reading Corp., Elizabeth, N.J., a corporation of New Jersey

Filed Apr. 24, 1963, Ser. No. 74,602

Term of patent 14 years

(Cl. D34—15)

Fig. 1

Des. 197,658

FIG. 1 is a right side elevation of the toy howitzer showing my new design. The left side is substantially a mirror image of the right side.

FIG. 2 is a view in perspective showing the front or muzzle end and right side of the design, and

FIG. 3 is a view in perspective showing the rear or trail end and left side of the design.

I claim:

The ornamental design for a toy howitzer, as shown and described.
